FRED M. YOUNG, OF RACINE, WISCONSIN

HUMIDIFYING APPARATUS FOR SPACE HEATERS

Application filed December 17, 1930. Serial No. 503,002.

This invention relates to improved humidifying apparatus, particularly for air heating devices.

The objects of my invention are to provide improved means for injecting moisture in the form of water, steam or water vapor from a heat interchanger into a forced current of air while the air is being passed through a heater; to provide automatic regulating means for regulating the quantity of moisture injected in proportion to the rate of movement of the air through the heat interchanger and proportional to the moisture absorbing capacity of the air supplied to the heater, to retain the atmosphere surrounding the heater at a substantially uniform relative humidity under various operating conditions of the heater; to provide regulating means which will completely shut off the discharge of moisture when the current of air through the heater is discontinued and to provide adjustable means for varying the quantity of moisture injected into the current of air independently of the rate of flow of the current and temperature of the surrounding air for predetermining the relative humidity of the atmosphere in the room.

In the accompanying drawings, I have illustrated the embodiment of my invention in which:

Figure 1 is a rear elevation of a space heater embodying my improved humidifying means.

Fig. 2 is a side elevation of the structure shown in Fig. 1.

Fig. 3 is an enlarged fragmentary section of regulating mechanism for controlling the discharge of moisture.

Fig. 4 is a section taken on the line 4-4 of Fig. 3.

Fig. 5 is a section taken on the line 5-5 of Fig. 3.

My improved humidifying apparatus is particularly suited for use in connection with space heaters in which a current of air is impelled through a heat interchanger supplied with steam or hot water. It may be constructed so as to inject the moisture into the air as it is being impelled through a heat interchanger or immediately thereafter.

In the illustration shown in the drawings, moisture dispensing means are provided in a supporting bracket for a motor driven fan or blower. The bracket has a flange on its end by means of which it may be attached to the upper header tank of a radiator of the same general type as that used in automobile construction and it is provided with a passage communicative with the interior of the tank. The passage extends rearwardly through the bracket and communicates with a plurality of nozzles for injecting moisture into the current of air.

A manually operable valve is provided at the forward end of the passage for determining the flow of fluid therethrough and a valve for automatically controlling the discharge of fluid from the nozzles is located at the rear end portion of the passage. The latter valve is provided with actuating mechanism which extends into the path of the air impelled by the fan for proportioning the discharge of moisture relative to the rate at which the air is impelled through the heater. A thermostatic valve extends into the passage between the manually operable valve and the automatically actuated valve for regulating the flow of moisture to the nozzle relative to the room temperature. The temperature and the air controlled valves may be used independently or simultaneously.

In the form shown, a space heater comprising upper and lower header tanks 1 and 2 respectively, and an intercommunicative core 3 is provided with an angular shaped supporting bracket 4. The upper extremity of the arm 4 is provided with a flange 4' having apertures therein for receiving the bolts 5' by means of which the bracket is attached to a face plate 6' on the upper header tank.

A fan comprising a motor 5 and a propeller 6 is mounted on the lower extremity of the arm 4. The propeller fan is located within a partial closure formed by the side plates 7 of the heat interchanger and overhanging portions on the header tanks 1 and 2.

A heating medium, such as water or steam, is supplied to the heat interchanger through the pipe 8 communicative with the upper header tank 1 and flows from the heat in-

terchanger through the pipe 9 communicative with the lower header tank 2. Some of the heating medium passes rearwardly through an aperture 11 in the face plate 6' of the upper tank 1 and through a passage 17 in a solid section 18 of the upper end portion of the bracket 4. The passage 17 extends rearwardly horizontally and communicates with a vertical passage 19.

10 A needle valve 21 is threaded in an aperture in the solid section 18 and extends into the passage 17 thereof for manually regulating the flow of the heating medium to the passage 19. The needle valve 21 is positioned diagonally, as shown in Fig. 4.

15 A thermostatic valve comprising a valve stem 22 and an expandible member 23 is mounted on the bracket 4 by a U-shaped strap 24. The member 23 bears between the strap 24 and a yoke 25 to which the stem 22 is rigidly secured. The lower end of the stem 22 is retracted from and extended into the passage 17 by the expansion and contraction, respectively, of the member 23, thereby regulating the flow of heating medium through the passage in proportion to the change of temperature which causes the expansion and contraction of the member 23.

20 A valve 26 for automatically controlling the flow of fluid from the passage 17 extends into the solid section 18 through a horizontal passage 27 and into the passage 17 where the latter passage meets the vertical passage 19. This valve is threaded in the solid section 18 and is provided at its outer end with a pinion 28. The pinion 28 is located on one side of the bracket 4 and is meshed with a gear segment 29 pivoted on the bracket 4 at 25. The gear segment 29 comprises an arm 31 provided with a vane 32 normally extending transversely of the current of air created by the fan. A spring 33, attached at one end to the bracket 4 and at its other end to the arm 31, normally retains the arm 31 and vane 32 in their rearward position. When the fan is in operation, the gear segment 29 is rotated in an anti-clockwise direction by the current of air created thereby and the pinion 28 is rotated in a clockwise direction 30 opening the valve 26 which is provided with left-hand threads.

35 A spraying device comprising a riser 34 communicative with the lower end of the vertical passage 19 in the solid section 18 is provided with a transverse pipe 35 having removable nozzles 36 mounted thereon. The pipe extends substantially across the width of the heat interchanger and may be provided with any desired number of nozzles, each of 40 which are positioned for directing a spray of moisture into the compartment in which the propeller 6 is confined.

45 The manually operable valve 21 may be set in any desired position for predetermining the maximum flow of the heating medium

from the header tank 1 to the spraying device. The thermostatic valve is lifted from and lowered into the path of the heating medium in the passage 17 when the temperature of the surrounding atmosphere raises and lowers respectively. In this manner a greater flow of moisture is supplied to the current of air, being impelled through the heat interchanger when the air is at a higher temperature.

50 This regulation tends to maintain the relative humidity substantially uniform in a room at different temperatures by supplying more moisture as the air becomes conditioned for absorbing greater quantities of moisture.

55 The automatic valve 26, under actuation of the spring 33 completely shuts off the flow of moisture to the spraying device when the fan is inoperative, thus avoiding the continued dripping of water. The automatic valve actuating mechanism also proportions the flow of heating medium or moisture to the rate at which air is passed through the heat interchanger thereby maintaining uniform air conditions at various rates of operation of the fan.

60 The nozzles 36 are removable and may be replaced by nozzles having discharge apertures of different sizes for adapting the device to discharge heating medium of different nature, such as steam and hot water.

65 Although but one specific embodiment of this invention has been herein shown and described, it will be understood that numerous details of the construction shown may be altered or omitted without departing from the spirit of this invention as defined by the following claims.

I claim:

70 1. An air conditioning device comprising means for impelling a current of air, a fluid reservoir comprising a restricted outlet for injecting moisture under pressure into said current of air, and automatic regulating means in said outlet for varying the amount of moisture injected in proportion to the quantity of air impelled and its moisture absorbing capacity for maintaining the surrounding air at a substantially constant relative humidity.

75 2. In combination with an air heating device comprising spaced tanks and intercommunicative tubes, a bracket having a passage therein communicative at one end with one of said tanks, a fan on said bracket for impelling a current of air through said heater, nozzles communicative with the other end of said passage for injecting moisture from said tanks into the current of air impelled by said fan as it is driven into said heater, a valve in said passage, and actuating mechanism comprising a vane operatively connected with said valve and extending into the path of the current of air for opening and closing said

valve when said fan is operative and inoperative respectively.

3. In means for conditioning air, in combination with a heater comprising spaced tanks and intercommunicative tubes, a fan for impelling a current of air through said heater, water vapor injecting means comprising a bracket attached to one of said tanks having a passage therein communicative with said tank and a distributing member communicative with said passage, nozzles removably mounted on said distributing member for injecting water vapor from said tank into the current of air as it is impelled through said heater, and means for regulating the flow of water vapor through said nozzles relative to the quantity of air impelled through said heater and relative to its moisture absorbing capacity for maintaining the surrounding atmosphere at a substantially uniform relative humidity.

4. The combination with a space heater comprising a fluid heating medium reservoir, of a fan for impelling a current of air through said heater, an extension on said reservoir having a passage therein communicative with the interior of said reservoir for injecting fluid into said current of air as it is passed through said heater, a needle valve threaded in said extension comprising a pinion, means for actuating said needle valve comprising a vane pivoted on said extension and extending into the path of said current, a gear segment on said vane meshed with the pinion of said valve for regulating the flow of fluid through said passage, and means for rotating said vane to completely close said passage when the fan is inoperative.

5. An air conditioning device comprising means for impelling a current of air, a fluid reservoir comprising a restricted outlet for injecting moisture under pressure into said current of air, an automatic regulating means in said outlet actuated by the flow of said current of air for varying the amount of moisture injected in proportion to the quantity of air impelled, and a second means actuated by the temperature of the surrounding air for controlling the amount of moisture injected according to the moisture absorbing capacity of said current of air.

Signed at Chicago this 8th day of October, 1930.

FRED M. YOUNG.
